A. L. FORSBERG

CONTAINER AND MANUFACTURE THEREOF

Filed Sept. 24, 1927

Inventor:
Albin L. Forsberg,
By Dyengenforth, C. Clinton Miller,
Miss.

UNITED STATES PATENT OFFICE.

ALBIN L. FORSBERG, OF CHICAGO, ILLINOIS, ASSIGNOR TO THE THOMSON & TAYLOR CO., A CORPORATION OF ILLINOIS.

CONTAINER AND MANUFACTURE THEREOF.

Application filed September 24, 1927. Serial No. 221,735.

This invention relates to improvements in containers and the manufacture thereof, and more especially to a container with a discharge opening having a readily removable closure.

One of the features of my invention is the provision of such a discharge opening which is easily and hermetically sealed after the container is filled, but which may be easily opened by the consumer.

In that form of device embodying the features of my invention shown in accompanying drawings, Figure 1 is a view in perspective of a completed container, Fig. 2 is a vertical sectional view of the cover for the discharge opening showing the same before being applied, Fig. 3 is a view in perspective of the discharge opening showing the same before applying the cover, Figs. 4 and 5 are vertical sectional views showing two steps in the applying of the cover to the opening, and Fig. 6 is a plan view of the ordinary key used by the consumer in removing the cover from the discharge opening.

In the practice of my invention, the top of the can as indicated by 10 is first provided with a discharge opening 11 surrounded by the annular upstanding flange 12. 13 indicates a circular cover for the discharge opening which is provided with an upstanding ridge 16 providing a groove underneath preferably filled with a suitable sealing compound or cement 14.

In the next step of manufacture, the cover 13 is applied over the opening, the flange 12 extending up into ridge 16 and becoming embodied in the sealing compound 14.

After the parts are in the position shown in Fig. 4, a press 17 is used to press the upstanding ridge 16 outwardly and flatten it down as shown in Fig. 5, thus making a tight seal.

The cover 13 is preferably provided with a narrow marginal flange 18 around its edge and at one point this flange is extended to form a tongue 19.

20 indicates the ordinary type of key provided with a slot 21 adapted to embrace the tongue or tab 19. In order to remove the cover 13 from the discharge opening the key is applied and the cap wound upon the same in the usual manner, such winding

serving to tear the same loose from the discharge opening.

While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty in my invention as broadly as possible in view of the prior art.

What I claim as new, and desire to secure by Letters Patent, is:

1. A container having a discharge opening in a wall thereof, and a removable cover for said discharge opening, said cover attached to said wall by an outwardly extending flange surrounding the discharge opening, said flange projecting into and tightly embraced by an outwardly extending flattened hollow ridge in the cover.

2. A container having a discharge opening in a wall thereof, and a cover for said discharge opening, attached to said wall and held in place by a flange surrounding the discharge opening and extending up into a ridge formed in the cover, said ridge and flange being pressed downwardly and outwardly tightly against the wall to cause the ridge to lock the flange therein and hold the same tightly.

3. The process of attaching a cover to a discharge opening in a wall consisting of providing an upstanding peripheral flange surrounding said opening in the wall, providing the cover with an upstanding hollow ridge adapted to receive said flange, applying the cover over the opening to cause the flange to extend up into the hollow ridge, and pressing downwardly the ridge and flange against the wall into a plane substantially parallel with the wall to cause the ridge to be compressed, to squeeze the flange therein.

4. The process of attaching a cover to a discharge opening in a wall consisting of providing an upstanding peripheral flange surrounding said opening, providing the cover with an upstanding hollow ridge adapted to receive said flange, applying the cover over the opening to cause the flange to extend up into the ridge, and pressing

downwardly and outwardly the ridge and flange against the wall to cause the ridge to be compressed, to squeeze the flange therein.

5. A container having a discharge opening in the wall thereof, and a removable cover for said discharge opening, said cover attached to said wall by an outwardly extending flange surrounding the discharge

opening, said flange projecting into and tightly embraced by an outwardly extending flattened hollow ridge in the cover lying against said wall. 10

In witness whereof, I have hereunto set my hand this 21st day of September, 1927.

ALBIN L. FORSBERG.
